UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR AN APPENDAGE FOR CASES OF WATCHES OR SIMILAR ARTICLES.

53,974.

Specification for Design.

Patented Oct. 14, 1919.

Application filed May 5, 1919. Serial No. 294,998. Term of patent 14 years.

To all whom it may concern:

Be it known that I, ARTHUR W. WADSWORTH, a citizen of the United States, residing at Fort Thomas, in the county of Campbell and in the State of Kentucky, have invented a new, original, and ornamental Design for Appendages for Cases of Watches or Similar Articles, of which the following is a specification, reference being had to the accompanying drawing, forming part thereof.

In the drawing:

Figure 1 is a front elevation of a case appendage embodying my design, its relation to a watch-case and to another similar appendage at the opposite edge of the case, and the strap, being indicated by a conventional showing of the latter by dotted lines;

Fig. 2 is a similar bottom view thereof;

Fig. 3 is a similar side elevation thereof, the indication of the ribbon being omitted;

Fig. 4 is an enlarged side elevation of the appendage, viewed from the opposite or inner side thereof;

Fig. 5 is an enlarged front elevation of the same.

I claim:

The ornamental design for an appendage for cases of watches or similar articles, substantially as shown.

ARTHUR W. WADSWORTH.
